MULTIPLIER

Filed Jan. 22, 1923

Witness:

Dr. Garrison.

Inventor:

Clinton F. Beery,
By Frank Wilson *Attn:*

UNITED STATES PATENT OFFICE.

CLINTON E. BEERY, OF CHICAGO, ILLINOIS.

MULTIPLIER.

Application filed January 22, 1923. Serial No. 614,056.

To all whom it may concern:

Be it known that I, CLINTON E. BEERY, a citizen of the United States, residing in the city of Chicago, in the county of Cook and State of Illinois, have invented certain new and useful Improvements in Multipliers, of which the following is a specification.

This invention pertains generally to arithmometers, and has more particular reference to a simple form of multiplier adapted for use by school children, to assist them in learning and memorizing the multiplication table.

The primary purpose of the invention is to provide a device of the character indicated, which will be extremely simple in construction and in operation, but which will be of great assistance to the pupil in that it enables him to visualize simultaneously the multiplicand, the multiplier, and their product.

For the purpose of facilitating an understanding of my invention, I have illustrated on the accompanying drawings a preferred embodiment thereof, from an inspection of which, when considered in connection with the following description, my invention, its mode of operation, and many of its advantages should be readily understood and appreciated.

Referring to the drawings:

Fig. 1 is a plan view of a multiplier embodying my invention;

Fig. 2 is a side elevation thereof; and

Fig. 3 is a sectional view on the line 3—3 of Fig. 1.

Referring to the drawings more in detail, reference character 5 indicates a board, plate, or the like, made of any suitable material, preferably sheet metal, and providing a flat surface adapted to receive a sheet of paper, cardboard, or the like, 6, upon which the products of the multiplication table are printed. These products are arranged in rows longitudinally and transversely of the board, as shown in Fig. 1, a horizontal row, indicated by reference character 7; being the products of the table of twos, row 8 the products of the table of threes, and so on. Likewise, the vertical row 9 comprises the products of the table of twos, row 11 the products of the table of threes, and so on. The top and bottom edges of the plate 5 are turned over to form the flanges 12 and 13, respectively, beneath which the edges of the sheet 6 are disposed, and the sheet is further

held in place by the flange 14 on the right-hand edge of the plate.

Upon the face of the plate there is mounted a guide member 15, which is supported some distance above the face of the board by the downwardly bent ends 16, which are anchored beneath the flanges 12 and 13, as shown in Fig. 3. A movable head 17, slidably disposed upon the member 15, is provided with an indicator opening 18, adapted to transverse a column of multiplicands 19, printed upon a strip 21 disposed in the channel formed by the member 15. The head is also provided with a guide portion 22 in which a bar 23 is slidably disposed and adapted to project across the face of the table. The extent of movement of this bar in both directions is limited by the upturned end 24 and the downturned end 25, respectively. The head 17 is also provided with another indicator in the form of a sight opening 26 disposed over the bar 23, through which the multipliers 27, printed on a strip 28 disposed in the upwardly opening channel 29 of the bar 23, may be observed. The outer downturned end of the bar is also provided with an indicator in the form of a sight opening 29, through which that multiplication product over which the sight opening 26 is disposed may be observed. A sheet of transparent material 31, such as celluloid, is preferably disposed over the face of the table, and strips of similar material are disposed over the multipliers and multiplicands 27 carried by the guide member and slide bar, respectively.

My multiplier is adapted to be used in the following manner. The user slides the head 17 along the guide 15 until the multiplicand indicator 18 is disposed over the desired multiplicand. The bar 23 is then adjusted longitudinally until the desired multiplier carried thereby is visible through the sight opening of the multiplier indicator 26. Due to the construction and arrangement of the parts, the product indicator 29 will then be disposed over the product of the indicated multiplicand and multiplier, and can be readily observed. For instance, assuming that 5 is to be multiplied by 12, the head 17 is adjusted to bring the sight opening 18 over the numeral 5 in the multiplicand column, the bar 23 is then adjusted to dispose the numeral 12 carried thereby beneath the multiplier sight opening 26, whereupon, as will be apparent from Fig. 1, the product in-

dicator sight opening 29 will be found to be disposed over the numeral 60 on the table which is the product of the indicated multiplicand and multiplier.

5 It is believed that my invention, its mode of operation, and many of its advantages should be understood from the foregoing without further description; and it should also be manifest that while a preferred embodiment of the invention has been shown and described for illustrative purposes, the structural details are nevertheless capable of wide variation within the purview of my invention, as defined in the following claims.

15 I claim:

1. A multiplier comprising a table of multiplication products, a column of multiplicands disposed adjacent thereto, a movably mounted head adapted to traverse said column and provided with a multiplicand indicator and a multiplier indicator, and a member carrying a series of multipliers movable upon said head and provided with a product indicator arranged to indicate on said table the product of any multiplicand and multiplier designated by their respective indicators.

2. A multiplier comprising a table of multiplication products, a column of multiplicands adjacent thereto, a member movable longitudinally of said column and provided with multiplicand and multiplier indicators, and a member movable transversely of said first mentioned member, carrying a series of multipliers adapted to be brought into registration with said multiplier indicator, said last mentioned member being provided with a product indicator adapted to indicate on said table the product of the designated multiplicand and multiplier.

3. A multiplier comprising a plate provided on one face with a table of multiplication products, a guide secured to said plate and provided with a column of multiplicands, a head slidably mounted on said guide and provided with a multiplicand indicator and a multiplier indicator, a bar slidably mounted in said head and movable therein perpendicular to the direction of movement of said head, said bar being provided with a series of multipliers and being equipped with a product indicator adapted to designate on said table the product of any selected multiplier and multiplicand.

4. A multiplier comprising a plate pro-

vided on one face with a table of multiplication products, the numerals thereof being arranged in vertical and horizontal rows, a guide member mounted on said plate 60 parallel with one side of said table and provided with a column of multiplicand numerals arranged parallel with one edge of said table, a head slidably mounted on said guide member and provided with a multiplicand indicator and a multiplier indicator, a bar slidably carried by said head, said bar being movable transversely to the direction of movement of said head and being provided with a series of multiplier numerals adapted to be disposed in cooperative relation to said multiplier indicator, and a product indicator carried by the bar in position to indicate on said table the product of the indicated multiplier and multiplicand 75 numerals.

5. A multiplier comprising a plate provided on one face with a table of multiplication products, a guide member mounted on said plate and carrying a column of multiplicands, a head slidably carried by said member and provided with multiplier and multiplicand indicators, a guide-way formed in said head and extending at right angles to said guide member, a bar slidably mounted in said guide-way with one end extending over said table, said bar being provided on its upper face with a series of multiplier numerals, and a product indicator carried by the projecting end of said bar in position to indicate on said table the product of the indicated multiplier and multiplicand.

6. A multiplier comprising a plate provided with marginal flanges, a sheet held in position on one face of the plate by said flanges and provided on the exposed face with a table of multiplication products, a channel shaped slide member elevated above the face of said plate and having its ends 100 downturned and anchored beneath the flanges of said plate, a strip disposed in the channel of said guide and provided with a column of multiplicands exposed to view at the top of said guide, a head slidably mounted on said guide, and a multiplier carrier slidably carried by said head, said head being provided with multiplier and multiplicand indicators and said multiplier carrier being provided with a multiplication product indicator.

CLINTON E. BEERY.
